UNITED STATES PATENT OFFICE

PETER KELLEY, OF WINSTED, CONNECTICUT

SAFETY-PIN HOLDER

Application filed June 3, 1927. Serial No. 196,384.

This invention relates to safety pin holders, and more particularly to a holder constructed from metal or other stiff material for holding the pins in upright position in 5 parallel rows.

One object of this invention is to provide a safety pin holder of the above nature in which the pins may be inserted and removed without opening said pins.

10 A further object is to provide a safety pin holder of the above nature in which the pins may be removed from the holder with the use of one hand only and without tearing or otherwise injuring the holder.

15 A further object is to provide a device of the above nature, which will be simple in construction, inexpensive to manufacture, easy to manipulate, compact, ornamental in appearance, and very efficient and durable in 20 use.

With these and other objects in view there has been illustrated on the accompanying drawings one form in which the invention may be conveniently embodied in practice.

25 Fig. 1 represents a perspective view of the safety pin holder as it appears after one of the safety pins has been placed therein.

Fig. 2 is a top plan view of the holder as it appears when it has been filled with safety 30 pins.

Fig. 3 is a side sectional view of the same.

It has been customary in the past to market safety pins on paper cards, the pins being fastened in place by having their points 35 passed through the card. This form of holder was objectionable on account of the fact that the pins were oftentimes carded under unsanitary conditions, as in sweat shops or homes of the operators. Moreover, to remove the pins from such cards, it was necessary either to open the pins or tear the card, both hands being required in each case.

40 By means of the present invention the above and other disadvantages have been avoided. This has been accomplished by providing a safety pin holder of stiff rigid material consisting of a flat base having a pair of end flanges upstanding therefrom, said flanges having alined apertures forming 45 seats for the caps and coils of the opposite

ends of the safety pins respectively. The safety pins are adapted to be held in the improved holder in parallel slightly spaced relation, whereby a much greater number of pins may be held in the same space than was 55 possible with the old form of card.

Referring now to the drawings in which like reference numerals denote corresponding parts throughout the several views, the numeral 10 indicates the base of the safety pin holder, said base being provided at its opposite ends with an upstanding cap flange 11 and a coil flange 12 respectively. The holder is preferably made from hard resilient brass, 60 although it is within the scope of the invention to construct the holder of any other stiff material such as celluloid, glass, bakelite, etc.

The flanges 11 and 12 are preferably curved outwardly, as most clearly shown in Fig. 3, so as to enable a safety pin 13 to be 65 readily inserted in the holder by forcing it from above in a downward direction. Each cap flange 11 is provided with a plurality of elongated cap sockets or apertures 14, said apertures preferably being slightly wider than the thickness of the safety pin cap 15 and slightly shorter than the width of said cap.

70 Each coil flange 12 is provided with a plurality of coil sockets or apertures 16 alined with the cap apertures 14, and preferably being elliptical in shape. The apertures 16 are preferably slightly wider than the thickness of the safety pin coil 17 and somewhat shorter than the width of said coil.

75 In operation, when it is desired to insert a safety pin in the holder, said pin will be held in an inclined position with its point leg 18 vertically below the cap leg 19. The coil 17 will then be placed in the proper coil socket 16 in the coil flange 12, and the cap end of the pin will then be swung down about the socket 16 as a pivot until the cap 15 engages the flange 11. The cap 15 will then 80 yield slightly in an inward direction owing to the resiliency of the cap leg 19. Continued downward pressure on the cap 15 will cause it to snap into the cap socket 14, whereupon the cap will be forced outwardly into 85 resilient engagement with said socket 14 into 90

the position shown in Fig. 3. The resiliency of the cap leg 19 will thereafter prevent removal of the safety pin until desired. The insertion of the pins into the holder may be 5 performed either by hand or by machine without opening the pins, thus effecting a considerable saving of time over the former carding process.

In removing a safety pin from the holder 10 it will merely be necessary for the operator, using one hand alone, to pull upwardly on the cap leg 19. In this operation, owing to the resiliency of the cap leg 19, the cap 15 will be caused to bend inwardly out of the 15 socket 14, releasing the pin therefrom.

A further advantage is that the holder may be used over and over again.

While there has been disclosed in this specification one form in which the invention 20 may be embodied, it is to be understood that this form is shown for the purpose of illustration only, and that the invention is not to be limited to the specific disclosure but may be modified and embodied in various 25 other forms without departing from its spirit. In short, the invention includes all the modifications and embodiments coming within the scope of the following claims.

Having thus fully described the invention, 30 what is claimed as new, and for which it is desired to secure Letters Patent, is:

1. In a safety pin holder, a base, and a pair of opposing apertured flanges upstanding from said base for detachably holding 35 the ends of a plurality of safety pins, said apertures being wider than the thickness of the respective ends of said safety pin and shorter than the width of said ends, whereby the pins will be held in parallel upstanding 40 spaced relationship.

2. In a safety pin holder, a base, and a pair of opposing diverging flanges upstanding from said base for detachably holding the ends of a plurality of safety pins, said 45 flanges having alined sockets shaped to receive the caps and coils respectively of the ends of a row of parallel safety pins.

3. In a safety pin holder, a base having a pair of opposing upstanding flanges for detachably holding the ends of a row of closed safety pins, said flanges having alined sockets shaped to snugly receive the caps and coils respectively of said safety pins.

In testimony whereof, I have affixed my 55 signature to this specification.

PETER KELLEY.
